UNITED STATES PATENT OFFICE.

JOHN G. MACPHERSON, OF BUFFALO, NEW YORK.

COIN-CONTROLLED MACHINE.

SPECIFICATION forming part of Letters Patent No. 611,071, dated September 20, 1898.

Application filed April 14, 1898. Serial No. 677,539. (No model.)

To all whom it may concern:

Be it known that I, JOHN G. MACPHERSON, a citizen of the United States of America, and a resident of Buffalo, in the county of Erie 5 and State of New York, have invented certain new and useful Improvements in Coin-Controlled Machines, of which the following is a specification.

My invention relates to improvements in 10 coin-controlled machines, and has special reference to a machine for automatically exhibiting pictures or photos to view.

The main object of my invention is the provision of a machine of this character in which 15 a coin forms a part of the electrical circuits to start an exhibiting mechanism to revolve a drum carrying pictures or photographs and at the same time light an electric light.

Another object of my invention is the provision of a machine of this character which 20 is very simple, durable, and inexpensive in construction and operation, very amusing and profitable in use and practice, as well as very attractive and ornamental in appearance, 25 thus producing a thoroughly efficient and effective and practical machine.

Figure 1 represents a front elevation of my machine. Fig. 2 is a horizontal sectional view looking from the top. Fig. 3 is a detail side 30 elevation of the coin-chute and circuit-maker. Fig. 4 is a detail longitudinal section of my machine. Fig. 5 is a perspective view of one of the picture or photo holders. Fig. 6 is a similar view to Fig. 4, taken from the opposite side of the machine. Fig. 7 is a detail perspective view of part of the coin-releasing mechanism. Fig. 8 is a similar view of the remainder of the coin-releasing mechanism. Fig. 9 is an enlarged view of the shaft and 35 gear driving mechanism. Fig. 10 is a diagrammatic view of the electrical circuits, their connections and various positions, the uses of the circuits being fully shown; and Fig. 11 is an enlarged view of the other or 40 modified form of driving mechanism.

In the drawings the numeral 1 designates the casing, in whose body portion 2 is arranged all the mechanism. Upon the front of this body portion is hinged a door 3, which allows 45 access to the working mechanism and also a view of part of the interior thereof, when closed, through the glass front 3^a, and it will

also be noticed that the sides of this body portion near the top are cut away to allow room for the removal of the slot-carrying section 4, whose top edge fits close under the slanting top piece 5, carrying the lens or observation-window 6, and to one side of said window is the electrical push-button 7, the purpose of which will appear hereinafter. 60

Depending from the shelf 8 of section 4, below the slot-opening 9, is the coin-carrying guide or chute 10, which is held in place from any forward or backward movement by an arm 11, which is secured to the under side of 65 said shelf. Also secured upon the under side of this shelf is a lug 12, which is engaged by the spring-actuated dog or detent 13, secured near the top edge of the back 14 of the inner shelf 15 to hold said slot-carrying section in 70 a rigid position.

Secured upon the bottom of the casing is the branch block 16, to which are connected the positive and negative wires 17 and 17^x of any electric current, which passes into the 75 casing from the rear through the opening 18.

To make the operation and construction of my machine more easy, I shall describe the circuits and their use and operation one at a time. 80

It will thus be seen that the wire 19 is connected to the rear of the branch block at 20 and passes upward and is connected with the push-button 7, another wire 21 then being secured to the other pole of the button and 85 passed along backward and connected to the incandescent electric lamp 22, secured upon the back of the casing, near the top, and another wire 23 is secured to the other pole of said lamp and passes downward and is connected to the branch block on its front side at 24. It will thus be seen that by pushing the button this circuit is completed and the lamp is lighted, as the circuit is completed by connection with the outside supply. 90

It will also be noticed that I secure a wire 25 to the same pole that I secure the wire 19 to and that said wire 25 passes slantingly upward through the opening 26 in the back 14 and is connected to the pole 27, secured 100 to the plate 28, having rising therefrom or formed integral therewith the standard 29, in whose upper end is pivoted the arm 30, carrying the depending wing 31 at its inner

end and the right-angled arm 32 at its other end, a spring 33 being secured upon the shelf and bearing upon the under side of the arm 32 to cause the wing 31 to press against the coin 34 and cause a circuit, as will presently appear. Upon this shelf, to one side of this plate 28, is another plate 35, having rising therefrom or formed integral therewith the slotted standard 36, through which is adapted to fall a coin and be held between the standards 29 and 36 by the wing 31 of the pivoted arm, after which it is released and falls through the slot 37 in the shelf into the coin-drawer 38, slidably mounted below said shelf.

15 Upon the plate 35 is a pole 39, to which is connected the wire 40, which is connected to the switch-block 41, and to the other pole of said block is connected a short wire 42, connected at its other end to the post 43, to which also is connected the wire 44, which passes through the opening 45 in the back of the shelf downward and is connected to the resistance-lamp or proper rheostat 46. A wire 47 is connected to the other pole of said lamp and passes upward through the opening 45 and is connected to the post 48 of the motor-carrying base 49, upon which is mounted the motor 50, and connected to the other post 51 of the base is the wire 52, which passes backward and out through the opening 53 in the back of the shelf and downward to the front of the branch block at 24. This circuit is the main circuit and operates the exhibiting mechanism.

35 Secured in the post 43, together with the wire 44, is the wire 54, which passes out through the opening 45 and upward out of the way of the exhibiting mechanism to where it is connected to the incandescent lamp 55, while upon the other pole of said lamp is connected the wire 56, whose other end is connected to the same post as the wire 23, which forms the remainder of the circuit, and thus it will be seen that the coin completes the circuit to operate the motor and light the lamp 55 at the same time, and it will also be seen that should the resistance-lamp be loosened from its socket the motor will be thrown out of operation, while the lamp remains lighted.

55 Mounted in the upper part of the casing, upon the inside thereof, is the exhibiting mechanism, which consists of a frame 57, secured to the side of the casing and having the perpendicular right-angular-arranged arms 58 formed integral therewith, and secured upon the ends of said arms or formed integral therewith is the metal strip 59. Journaled between this strip and frame is the shaft 60, carrying the sprocket or gear wheel 61, which meshes with the worm-gear 62 upon the end of the long shaft or rod 63, whose upper end is journaled in the adjustable bearing-block 64, secured to said frame, and whose lower end is journaled in the bearing 64^a. Upon the lower end of this shaft is a gear-wheel 65, which meshes with the worm-

gear 66, secured upon the shaft 67 of the electric motor which operates the shaft. Secured upon the outside end of the shaft 60 is a slotted plate 68, having its ends 69 bent at right angles for the reception of the lug 70 upon the end of the removable shaft 71, which carries the circular disks 72 and 73, between which are movably secured in the openings 74 the rods 75, having movably mounted thereon the picture or photo carrying device 76, which consists of the back 77, having the upturned edges 78 to grasp and hold the pictures in place. The other end of the main shaft is movably journaled in the depending outwardly-tensioned flatspring-arm 79, which allows the picture-drum to be very readily moved from the machine to be filled or re-filled as desired. Upon the end of the shaft, near the spring-journal, is an arm 80, which is adapted upon every revolution of the drum to contact the lever 81, whose inner end passes through the long opening 82 of the frame 83 and is fulcrumed in the short arm 84 of said frame. On the side of the short arm is a screw 85, upon which is secured a wire spring 86, whose short end bears upon the top of the frame, while its long end 87 is hooked and engages the lever 81 to return the lever to its normal position when released from engagement with the arm 80. When the lever 81 is forced downward, it forces the rod 88 also downward, said rod having its upper end secured in the opening 89 of said lever and passing through the eyed lug 90, near the lower end of the frame, and below which the lower end of said rod contacts the right-angled arm of the pivoted arm 32, which releases the coin from engagement and allows it to fall into the coin-drawer and at the same time causes a circuit through said arms 32, rod 88, lug 90, and the foot 89' of the frame, to which is connected the wire 90', whose other end is connected to the post 91 of the slotted standard 36, thus completing another circuit with the remaining wires of the main circuit. Upon the foot 89' of the frame 83 is the adjustable non-conducting stop 90^a, which prevents the pivoted arm from making a short circuit through said frame. It will also be noticed that when the arm upon the drum's shaft engages the lever the lever is forced downward into engagement with a flatspring-plate 92, secured upon the side of the casing, and that connected to this plate is a wire 93, which passes downward and through the opening 45, where its other end is connected to the post 94 of the electrical arm or bell 95, and connected to the other post 96 is another wire 97, which passes backward and out through the same opening, thence downward, where it is connected to the post 98 of the dry or wet battery 99, to whose other post 100 is connected the wire 101, which is passed upward and connected to the upper end of the spring 79, and thus it will be seen that another independent circuit is completed every revolution of the picture-drum to ring the bell or

alarm and warn the observer that the pictures have all been presented to view and also to warn the proprietor that the machine has been put in operation.

- 5 To keep the pictures from falling too soon, I secure upon the back of the shelf the spring-clip 102, whose free end 103 is curved downward, so as to allow the pictures to drop smoothly and evenly.
- 10 In the modified form of my invention shown in Fig. 10 in place of the shaft with the sprocket and worm gears I employ the band or cord 104, which connects in operation the pulley 105 upon the end of the motor-shaft 15 and the pulley 106 upon the shaft 107, journaled in the frame 108.

From this description, taken in connection with the drawings, the operation of my machine is readily understood; but, briefly 20 stated, it is as follows: To obtain a view of one picture, it is simply necessary to push the button, which lights the electric light upon its circuit; but to obtain a view of all the pictures it is necessary to drop a coin in the slot, 25 from whence the coin falls down the chute to the slotted standard, where it is held by the pivoted arm and completes two circuits—that is, one which lights the lamp in the upper left-hand corner and the other which operates the 30 motor, which in turn revolves the drum-revolving mechanism to revolve the drum. Said drum being revolved the short arm on its shaft engages the spring-actuated lever, which releases the coin and causes the same to drop 35 by pressing the pivoted lever downward and thus switches the circuit from the coin to the intermediate frame; and when the spring-actuated lever is near its limit of movement it engages the spring-plate, which causes a 40 circuit between the bell, battery, and spring bearing-plate and causes the bell to ring, and when the drum has completed its revolution the short arm on the shaft is disengaged from the spring-actuated lever, which is returned 45 to its normal position and the circuits are all broken and the mechanism comes to a halt.

It is very evident that I provide a machine of this character which is operated solely by the use of a coin, which forms or closes the 50 circuit; which has a picture-carrying drum, which presents the pictures in front of the universal lenses, which are always adjusted to suit the eyes; which is simple, durable, and cheap in construction and operation; which 55 may be run or supplied by any kind of an electrical current, and which is very useful and practical for the intended purposes.

I claim—

1. In a coin-controlled picture-exhibitor, 60 the combination with a casing, of the picture-exhibiting mechanism arranged therein, an electrical circuit for revolving the picture-exhibiting mechanism and lighting an electric light, and another electrical circuit for 65 ringing an alarm, when the exhibitor is near-

ing its full revolution, said first-mentioned circuit being made by a coin and the last-mentioned circuit being made simultaneously with the release of the coin.

2. In a coin-controlled machine, the combination with a casing, of an electrical circuit caused by the coin to operate a motor, a picture-holding drum operated by said motor, an arm secured upon the shaft of said drum adapted to cause the release of the coin and 70 complete another circuit to continue the revolution of the drum, another circuit working in connection with the aforesaid circuit to light an electric light, and an observation-window through which the pictures are observed during the revolution of the drum.

3. In a coin-controlled machine, the combination with a casing, of an electrically-operated mechanism, a rod carrying at one end a worm-gear and at the other end a gear-wheel 85 operated by said electrical mechanism, a frame having journaled therein the short shaft carrying a worm-gear adapted to mesh with the gear-wheel upon said rod, a removable shaft carrying disks between which are 90 mounted movable picture-holders and having means secured on the shaft for releasing the coin and operating an alarm.

4. In a coin-controlled machine, the combination with a casing, of a revoluble picture-exhibiting drum mounted therein, mechanism for revolving the drum, an electrical circuit for operating said mechanism, a second electrical circuit for lighting a lamp simultaneously with the revolving of the drum, 100 said circuits being completed or formed by a coin, and a third electrical circuit for ringing an alarm when the exhibitor is nearing the end of a revolution.

5. In a coin-controlled machine, the combination with a casing, of a spring-bearing mounted upon one side of and upon the inside of the casing, a frame mounted upon the other side of the casing and carrying a revolving mechanism and a revolving bearing, 105 a detachable picture-exhibiting drum having an arm on one end of its axle mounted between said spring-bearing and said revolving bearing, a motor for operating the mechanism in the frame and the drum, electrical circuits 110 for operating the motor and lighting an electric light at the same time, circuits adapted to be made by the coin, and a coin-releaser set in operation by the said arm on the axle 115 of the drum to release the coin and make another electrical circuit to ring an alarm and forming or continuing the other circuits also 120 to continue the movement of the drum.

Signed by me, at Washington, District of Columbia, this 7th day of April, 1898.

JOHN G. MACPHERSON.
